UNITED STATES PATENT OFFICE.

HERBERT L. TRUBE, OF MISHAWAKA, INDIANA, AND WILLIAM S. FORD, OF CHICAGO, ILLINOIS, ASSIGNORS TO FORD-TRUBE COMPANY, OF CHICAGO, ILLINOIS, A CORPORATION OF ILLINOIS.

ADVERTISING-SIGN.

1,258,830.

Specification of Letters Patent. Patented Mar. 12, 1918.

Application filed February 21, 1916. Serial No. 79,573.

To all whom it may concern:

Be it known that we, HERBERT L. TRUBE and WILLIAM S. FORD, citizens of the United States, residing, respectively, at Mishawaka, 5 in the county of St. Joseph and State of Indiana, and Chicago, in the county of Cook and State of Illinois, have invented a new and useful Advertising-Sign, of which the following is a specification.

10 Our invention relates to improvements in advertising signs, and particularly to that class thereof which include a movable endless strip or web upon which appears the advertising or other matter to be exhibited.

15 The objects and advantages of our invention will hereinafter appear, and the novel features thereof be particularly pointed out in the claims.

Referring to the drawings:

20 Figure 1 is a perspective view of an advertising sign embodying our invention;

Fig. 2 is a rear elevation, the lid being shown in its raised position;

25 Fig. 3 is a horizontal sectional view on the line 3—3 of Fig. 1;

Fig. 4 is a bottom plan view, the bottom of the casing being removed;

30 Fig. 5 is a vertical transverse sectional view taken on the line 5—5 of Fig. 3; and Fig. 6 is a detail view hereinafter referred to.

Like numerals of reference indicate like parts in all the figures of the drawings.

We have herein illustrated a form and construction of casing and web-operating 35 mechanism believed by us to be best adapted for the purposes in view, but it will be understood that the casing as well as the mechanism therein contained may be varied in design and construction from that shown and

40 described and that at present we are merely illustrating and describing what we believe at this time to be the most practical form of apparatus.

With this understanding, and for the purpose of illustrating our invention, we refer more particularly to the accompanying drawing, wherein, it will be seen, that the casing comprises a front face-plate 1, which, like the remainder of the casing hereinafter

50 described, is preferably formed of stamped sheet-metal. In rear of and secured to the face-plate in any simple manner best adapted, as, for instance, by strips of angle-iron 2, is the box-like receptacle 3, which, as will

hereinafter appear, houses the endless web 55 and the parts employed for moving the same. A lid 4, may be hinged, as at 5, to the end-walls of the receptacle-portion of the casing, in order that access to the latter may be readily obtained, and a simple device for securing the lid in its elevated position may be provided. As, for instance, the lid may be formed with a narrow slot 6, one edge of which is designed to engage with and catch over a correspondingly located spring- 60 tongue 7, extending rearwardly, from the face-plate 1.

The receptacle 3 is preferably subdivided longitudinally by a horizontal partition 8, thus forming upper and lower compartments 70 9 and 10, respectively, the former being utilized, in this instance, for containing the endless web and the means for moving the same, and the latter compartment for containing the driving-mechanism, where such 75 is employed. We prefer to operate the web-operating mechanism by power, as, for instance, an ordinary electric-motor. To this end, therefore, we mount within the lower chamber 10, a conventional form of electric- 80 motor 11, the same deriving its current through the usual conductors 12, connected to a socket 13. On the arbor or shaft of the motor may be mounted a pulley 14 (see dotted lines, Fig. 4,) and such is connected to 85 a much larger pulley 15, located at the opposite end of the same compartment, by means of a drive-belt 16. An ordinary type of spring-actuated belt-tightener, 17, may be mounted upon and secured to the wall of 90 the compartment, and serve to maintain the belt under proper tension to obviate slipping.

The pulley 15 is mounted upon and adapted to rotate with a vertical shaft 18, the 95 latter being journaled in suitable cross-pieces 19, and extended upwardly through the partition 8, into the upper compartment 9, where it terminates and is preferably provided with a frictional surface, as, for instance, a rubber sleeve 20, which sleeve with the shaft constitutes what might properly be termed a friction feed-roller.

Secured to the upper side of the partition 8, which partition really constitutes the 100 floor of the compartment 9, is a three-sided partition 21, such comprising opposite rearwardly disposed end-walls 22 and 23, re-

spectively, and a longitudinally disposed connecting wall 24. This partition is preferably formed of comparatively light sheet-metal, bent to shape, and the upper edge is 5 horizontally bent and disposed to form a flange 25. This flange performs the function of stiffening the metal.

The end of the flange 25, may be extended beyond the end-wall 22, with which it is co- 10 incident, and there terminate in an enlarged disk-like head 25^a, the same being immediately above and out of contact with the friction feed-roller 20. This disk-like head 25^a, as will hereinafter appear, serves as an 15 efficient stripper for the feed-roller, which function it will serve by reason of the fact that it is stationary while the roller rotates or revolves. By this combination or arrangement, the natural tendency of the web, 20 especially if the latter is made of very light paper, to follow around the roller and adhere thereto, is obviated entirely.

The longitudinally disposed connecting-wall 24 of the partition 21, extends parallel 25 with the face-plate 1, which latter, at a point opposite said upper compartment 9, is provided with a longitudinally disposed sight-opening 26. Between the face-plate and the connecting-wall of the partition 21, and held 30 by any suitable means, may be located a transparent panel or pane 27, so that, as will be obvious, a web bearing any advertising-matter, printed or otherwise applied thereto, and passed through the space 28, 35 formed by the said panel and the connecting-wall 24 of the partition, will be plainly visible from without. The illuminating means may be located at any point desired with relation to the apparatus and so as to 40 show up the advertising matter to the best advantage as it is brought into view.

A spring-pressed roll 29, is maintained in contact with the friction-roll 20. Any desired means may be employed for this purpose, but we prefer that shown, wherein the roll is journaled in the opposite ends of a vertically disposed yoke 30, carried at the free end of a reversely bent spring 31, one end of the spring being secured to the end- 50 wall of the compartment 9, and the opposite end of which, after being reversely bent, as at 32, may be under adjustable tension by means of an adjustable screw 33, threaded in the wall of the said compartment. This 55 completes the enumeration and description of the parts that may be located in the feed-side of the upper compartment 9, with the exception of an idle guide-roll 34, or its equivalent, which is mounted on a vertical 60 stub-shaft 35, located beyond the discharge-end of the web-receiving space or passage 28, and designed to smoothly guide the web as it emerges from the passage to the said rolls 20 and 29.

65 In order to guide the web safely, posi-

tively, and with as little friction as possible about the opposite end or corner of the partition 21, and into the web-receiving passage 28, devices are located at the end of the partition at its end-wall 21 and between it 70 and the receiving-end of the web-passage. Such devices may vary in form and design

from those herein shown, but we have found that the latter will serve the purpose and cause the thin web of paper to approach 75 and enter the receiving-end of the web-passage in a perfectly smooth and even condition; hence, we prefer to employ them. We flare the receiving-end of the web-passage,

by connecting to the end-wall 23, where it 80 merges into the longitudinal wall 24 of the partition, a curved guide-plate 36, the disposition of the plate being toward the adjacent end of the casing and rearward, and therefore, of substantially quadrant-shape. 85 To reduce friction and avoid any sharp edges that might cause wear, the free end of the plate 36 may be bent or folded upon itself, as at 37. Beyond the curved guide-plate, overlapping the same, and attached 90 to the side of the casing, is a combined tension and smoothing-device. That is to say, a device that will give a light tension to the web and which will also tend to smooth out the same. In practice, we have found that 95

a bristle-brush, as 38, serves this purpose, the bristles of the brush being disposed in the direction of travel of the web. Beyond the rearwardly disposed end 23 of the partition, and which, in conjunction with the side-wall 100 of the casing, forms the outlet to the web-storing-chamber formed by the partition, we prefer to locate an idle guide-roller 40, mounting the same to freely revolve or rotate upon a vertical stub-shaft 39, extending upwardly from the floor of the compartment. This roller serves to guide the web as it leaves the storage-chamber, and its periphery is in substantial alinement with the curved guide-plate 36. In order to give 105

a slight tension between this roller and the aforesaid plate, and so as to assist the brush in smoothing out any folds or wrinkles, we may also use and employ between the roller 40 and the curved guide-plate, a vertically 115 disposed friction-device, in this instance, a curved rib 42. This friction-device, which may be in other form than that shown, if desired, it will be observed is out of alinement with the periphery of the roller 40 and the free edge of the apron 36, so that the web's course between these two points is somewhat tortuous.

In the form of apparatus we have described and illustrated, the web, which we 125 have indicated as A, and shown in position by heavy dotted lines in Fig. 3, may be of and preferably is of thin paper of sufficient stiffness to assure it being self supporting; that is to say, remaining on edge and capable 130

of freely gliding over the floor 8 of the storage-chamber. This not only results in cheapness, but secures the more important result of increasing the length of web capable of being stored within the web-storage chamber formed by the three walls of the partition and the rear wall of the casing, whereby the apparatus itself may be made compact and relatively small as compared to the length of web which it cares for. The web, it will be understood, is stored within the web-storage chamber in loose layers or folds and in a somewhat zig-zag form, and being endless, it is fed or stuffed by the rollers 20 and 29 into the chamber in this manner, being stripped therefrom by the stripper 25^a. As will be seen, the feeding or stuffing of the web into the web-storage chamber will also serve to draw the web from the opposite end of the chamber, so that the same is caused to follow the web-passage and as it passes the transparent panel whatever advertising matter is carried thereby will be observable through said panel. In this manner, and with a comparatively small apparatus, very long advertisements may be successfully exhibited. The web, it will be observed, as it is stuffed or fed into the feed end of the web-storage chamber and drawn from the discharge end thereof, glides lightly on edge over the smooth unbroken floor 8 of the chamber, so that, it can never get out of alinement, and hence, devices for obviating such are unnecessary. That is to say, the web is self-supporting and self-guiding, when thus mounted on edge.

From the foregoing it will be seen that the advertisement bearing web may be made of a length only limited by the capacity of the storage-chamber of the apparatus, and that only that portion thereof being exhibited at the moment is under tension between the tension-devices, the residue being stored, as described, in the storage-chamber and continuously shifting its position as it continuously approaches the exit thereof by being withdrawn from the opposite end. During all of such time, the stored portion of the web, as well as that comparatively small portion being exhibited, glides on its lower edge over the smooth unbroken surface of the horizontal partition or floor 8 of the storage-chamber.

Having described our invention, what we claim, is:

1. In an advertising apparatus, a casing having a sight-opening, guides located at the opposite ends of said opening, and an adjacent storage-chamber having an inlet and an outlet opening adjacent said guides, and a transverse floor, in combination with a uniformly and continuously flexible endless web of greater length than double the distance between said guides and mounted

upon the same so as to be supported thereby immediately in rear of said sight-opening, said web being of sufficient stiffness whereby its surplus portion will stand on edge and unaided upon and is free to glide over the floor of said storage-chamber and to fold in irregular vertically disposed layers within the latter, and means for feeding the web into the storage-chamber and withdrawing the same therefrom through the inlet and outlet openings respectively of said chamber.

2. In an advertising apparatus, a casing having a sight-opening, and a parallel web-guiding passage immediately in rear thereof, in combination with a storage-chamber within the casing provided with an inlet and an outlet opening and with a horizontal floor, an endless and uniformly continuously flexible web exceeding in length double the distance between ends of the web-guiding passage, said web being of sufficient stiffness whereby its surplus portion will stand on edge and unaided upon and is free to glide over the floor of said storage-chamber and to fold in irregular vertically disposed layers within the latter, a pair of rolls operating in frictional contact and vertically mounted in the feed-opening of said storage-chamber and adapted to feed said web therein and to simultaneously withdraw said web from the discharge opening of said chamber, and a stripping means for guiding said web from said feed-rolls after the web has passed between them and into the chamber.

3. In an advertising apparatus, the combination with a casing having one of its walls provided with a sight-opening, of a partition arranged in the casing and combining with that wall of the casing having the sight-opening to form a web-receiving passage and with the opposite wall of the casing to form a web-storage chamber, one end of the partition being rearwardly disposed and terminating short of the rear wall of the casing to form a feed-opening for the chamber, said chamber provided at the opposite side with a discharge-opening, said partition, at its end, being bent and rounded to form a stripper at one side of said feed-opening, opposite spaced apart web-guiding means adjacent the web-receiving passage, means located in the feed-opening of the chamber for feeding a web into the chamber and withdrawing it therefrom, and a uniformly and continuously flexible endless web mounted in the web-receiving passage and about the web-guides and of greater length than the distance between the same and having its surplus portion stored in irregular folds and standing on edge within the chamber and free to glide over the floor of the same.

4. In an advertising apparatus, the combi-

nation with a casing having one of its walls provided with a sight-opening, of a partition within the casing and spaced from the wall having the sight-opening to form a 5 web-receiving passage and at its ends external spaces and feed and discharge-openings, web-feeding and drawing-means located in the feed-opening, guiding means located in the discharge-opening, means for 10 operating the web-feeding and drawing-means, a curved guide-plate extending from the receiving-end of the web-passage and into the space at one side of the partition, a combined smoothing and tension-device 15 overlapping said guide-plate, a web-guide at the opposite end of the passage, and a uniformly and continuously flexible endless web of greater length than double the distance between said guide-plate and guide 20 and mounted in the receiving-passage, said web being of sufficient stiffness to stand unaided and having its surplus portion stored within the chamber and standing vertically on edge and in irregular layers and free to 25 glide over the bottom of the same.

5. In an advertising apparatus, the combination with a casing having one of its walls provided with a sight-opening, of a partition arranged in the casing and spaced 30 from the wall thereof having the sight-opening to form a web-receiving passage, and at its ends rearwardly bent to form external spaces and feed and discharge-openings for a chamber in rear of the passage, 35 web-feeding means located in the feed-opening, web-guiding means located in the discharge-opening, means for operating the feeding-means, a curved guide-plate extending from the receiving-end of the web-passage and into the space beyond the partition, a flat bristle brush located in said space 40 and overlapping the curved guide-plate, a guide at the opposite end of the web-passage, and a uniformly and continuously flexible 45 endless web in the passage and about said guide-plate and guides and of greater length than the distance between the same, said web being of sufficient stiffness to stand vertically unaided and having its surplus

portion standing on edge and in irregular 50 layers and stored in the chamber and free to glide over the bottom of the same.

6. In an advertising apparatus, the combination with a casing having one of its walls provided with a sight-opening, of a partition 55 arranged in the casing and spaced from and combining with that wall thereof having the sight-opening to form a web-receiving passage, the ends of the partition being rearwardly disposed and combining with the remaining walls of the casing to produce opposite external end spaces and an intermediate storage-chamber having feed and discharge-openings, a web-feeding and drawing means located in the feed-opening, web-guiding means located in the discharge-opening, means for operating the web-feeding and drawing-means, a flat horizontal smooth surface forming the bottom of the casing, 60 opposite guides at the ends of the web-receiving passage, one of said guides being a curved guide-plate extending from the receiving end of said passage and into the space beyond the partition and substantially in alinement with the web-discharging 65 means, a combined smoothing and tension-device overlapping the said curved guide-plate, a tension-device intermediate the curved guide-plate and the web-discharging means and out of alinement therewith, and 70 a uniformly and continuously flexible endless web mounted for movement in the web-receiving passage and exceeding in length the distance between the guides of the passage, the surplus of said web being stored 75 on edge in irregular folds in the chamber and free to glide over the bottom thereof.

In testimony whereof we have signed our names to this specification in the presence of two subscribing witnesses.
